FOUR-CYLINDER OFFSET ROTARY
MACHINEFritz Wolff, Plauen, Germany, assignor to
Vomag-Betriebs-A.-G., Plauen i. V.Application May 25, 1934, Serial No. 727,555
In Germany June 17, 1933

5 Claims. (Cl. 101—143)

This invention relates to a cylinder starting and stopping device in a four cylinder rotary offset machine.

It is known to arrange the axes of the rubber and plate cylinders in four cylinder rotary offset machines in a common plane and to remove the cylinders from each other in this plane in order to throw off impression. The known adjusting devices suffer, however, from the drawback that the contact of the grooves provided in the rubber cylinders for fixing the blankets causes vibrations which interfere with the uniform transfer of the impression from the plate cylinders to the rubber cylinders.

To eliminate this drawback and insure reliable arrangement of the impression cylinders the invention provides that one of the two plate cylinders remains stationary whereas the adjacent rubber cylinder is slightly removed therefrom during throwing off and the next rubber cylinder is moved twice this distance, and the other plate cylinder, with the respective inking apparatus and damping device, is disposed in a movable frame and displaced by the latter to such an extent that a sufficient space is provided between the plate cylinder and its rubber cylinder. To insure satisfactory transfer of the impression to the paper in spite of the adjustability of this plate cylinder and reliably take up the resulting counter pressure of the plate cylinder and transmit it to the machine frame, it is advisable to support the bearing carriage of the adjustable plate cylinder by means of a wedge in the direction of displacement during printing relative to a stationary machine wall and thus transmit the abutment forces in straight direction to the machine frame.

On the accompanying drawings one form of the invention is illustrated in Figure 1 in vertical section and Figure 2, which is a diagrammatic side view, shows the device for lifting the inking rollers.

Referring to the drawings, the paper web 1 to be printed is fed between the two rubber cylinders 2 and 3 in known manner and printed on front and back. The rubber cylinders 2 and 3 cooperate, respectively, with plate cylinders 4 and 5 provided with the usual inking apparatus and damping means. The axes of the cylinders 2, 3, 4, 5 are arranged in a common plane, in which the lines of contact of every two adjacent cylinders will thus be disposed also during the printing process.

The plate cylinder 5 with its appurtenant inking

apparatus 6 is stationarily positioned in the machine frame.

The two rubber cylinders 2 and 3 are supported by two eccentric bushes 39 possessing, respectively, the toothed rim segments 7 and 8 which engage a common toothed wheel 9 and are turned by the latter always through equal angles. However, the eccentricity of the bushes is chosen so that at a certain angular turn of the wheel 9 and a corresponding displacement of the two bushes the rubber cylinder 3 will be moved away from the stationary plate cylinder 5 to the extent of about 2 mm. and the rubber cylinder 2 about 4 mm. with the result that when the impression is thrown off a space of 2 mm. will remain between the plate cylinder 5 and the adjacent rubber cylinder 3 and also between the two rubber cylinders 2 and 3.

The plate cylinder 4 with its inking apparatus 10 and damping device 11 is positioned in a carriage 12 which is displaceably supported by the rolls 13 on an edge of the machine frame 14. Each side of the carriage 12 is fitted with a roll 15, the rolls being rotatably disposed and engaging cam discs 16 movably disposed on the machine frame 14 by means of the shaft 17. The shaft 17 carries also an adjusting lever 18 connected with an intermediate lever 20 by the rod 19. The intermediate lever 20 is secured to the shaft 21 passing transversely through the machine frame 14 and carrying a lever 22 which, together with the connecting rod 23 and the throw-off lever 24, serves for turning the shaft 21 when the machine is to be started or stopped. The shaft 21, by means of the lever 25, the coupling bar 26 and the auxiliary lever 27, turns also the wheel 9 by means of which the rubber cylinders 2 and 3 can be thrown on and off in the manner described. The cam discs 16 are shaped so that on their rotation the carriage 12 is sufficiently displaced to provide sufficient space during throwing-off between the plate cylinder 4 and the laterally displaced adjacent rubber cylinder 2.

During the displacement of the plate cylinder 4 the respective inking rollers of the inking apparatus 10 can be lifted off from the cylinder in known manner by a mechanical device moved preferably from the shaft 21 as shown in Figure 2.

To transmit in printing position the counter-pressure exerted by the plate cylinder 4 in a reliable manner to the machine frame without exposing the carriage 12 to the danger of tilting rearwardly, the rear edge of the carriage 12 is

provided with an abutment 28 whereas the vertical column 29 of the frame 14 carries a supporting surface 30. Between the parts 28 and 30 a wedge 31 is provided which can be raised and lowered by means of the link 32, the double-armed lever 34 rotatable on the bolts 33, the coupling bar 35 and the lever 36 positioned on the shaft 17. During displacement of the carriage 12 when the impression is thrown off the wedge 31 is first slightly lifted before the carriage, under the action of the cam disc 16, begins its lateral motion, whereas when the cylinders are brought into printing position first the cylinders 2, 3, 4 are placed in working position and then the wedge 31 locks the carriage 12 in printing position. The wedge 31 can be placed so low as to be approximately on a level with the axis of the cylinder 4.

It is not absolutely necessary to dispose the carriage 12 displaceably on the machine frame 14, since it would be possible to support all the parts to be carried by it in a frame which could be movable about a shaft disposed on the sole plate of the machine frame.

25. To prevent the carriage 12 from rising in printing position and thus cause a displacement of the cylinder 4 in vertical direction relative to the rubber cylinder 2, a ledge 37 is provided on the carriage which engages a projection 38 of the machine frame 14 when in printing position.

I claim:—

1. In a four cylinder offset rotary machine, in which the axes of two rubber and two cooperating plate cylinders are disposed in a common plane and movable relative to one another for throwing off impression, inking and damping means for the plate cylinders, one of the plate cylinders being stationarily disposed in the machine frame, eccentric bushes for supporting the rubber cylinders, toothed rim segments forming part of said bushes, a toothed wheel in mesh with said segments, driving means for said wheel, a carriage carrying the other plate cylinder and displaceably supported by the machine frame, and means connected with said driving means for said toothed wheel for displacing said carriage during stop-impression and removing the rubber cylinders from one an-

other and from the stationary plate cylinder to a predetermined degree.

2. In a machine according to claim 1 a wedge for supporting the carriage in the direction of displacement during printing relative to a stationary machine wall.

3. In a machine according to claim 1 a ledge arranged on the side of the carriage facing the inking means and a projection on the adjacent edge of the machine frame, said ledge engaging said 10 projection during printing to prevent rising of the carriage.

4. In a four cylinder offset rotary machine, in which the axes of two rubber and two cooperating plate cylinders are disposed in a common plane 15 and movable relative to one another for throwing off impression, inking and damping means for the plate cylinders, one of the plate cylinders being stationarily disposed in the machine frame, means for supporting said rubber cylinders having 20 toothed rim segments, a toothed wheel in mesh with said segments, driving means for said wheel, a carriage carrying the other plate cylinder and displaceably supported by the machine frame, and means connected with said driving means for said 25 toothed wheel for displacing said carriage during stop-impression and removing the rubber cylinders from one another and from the stationary plate cylinder to a predetermined degree.

5. In a four cylinder offset rotary machine, in 30 which the axes of two rubber and two cooperating plate cylinders are disposed in a common plane and movable relative to one another for throwing off impression, inking and damping means for the plate cylinders, one of the plate cylinders being stationarily disposed in the machine frame, means for supporting said rubber cylinders, driving means for driving said rubber cylinders, a carriage for carrying the other plate cylinder and displaceably supported by the machine frame, and means connected with said driving means for the rubber cylinders for displacing said carriage during stop-impression and removing the rubber cylinders from one another and from the stationary plate cylinders to a predetermined degree.

FRITZ WOLFF.
